HANDLEBAR

Carlton P. Pawsat and Robert F. Humlong, Maysville, Ky., assignors to Wald Manufacturing Company, Inc., Maysville, Ky.

Filed Sept. 21, 1970, Ser. No. 25,085

Term of patent 14 years

Int. Cl. D12—16

U.S. Cl. D90—11

FIG. 1 is a front 45° elevational view of a handlebar showing our new design.

FIG. 2 is a sectional view on line 2—2 of FIG. 1.

The characteristic features of our design reside in the configuration and appearances of the reflective surfaces on the risers of the handlebar.

We claim:

The ornamental design for a handlebar, as shown and described.
